RAZOR

Charles R. Bennett, East Cleveland, Ohio

Application July 24, 1946, Serial No. 685,841

3 Claims. (Cl. 30—47)

1

This invention relates to shaving devices especially to a novel type of razor.

Heretofore, various kinds of razors have been provided and they have been received with varying degrees of approval dependent upon the specific razor and its intended use. One difficulty with all types of razors known to me is that such devices have been bulky or were otherwise objectionable when one wanted to travel with little or no other luggage than shaving equipment. When traveling, it is important that the shaving equipment be compact when stored, particularly if one is traveling lightly. Also, in many instances, one might desire to carry his shaving equipment with him and shave at a later time at whatever place he was when time and opportunity for shaving presented themselves.

The general object of this invention is to avoid and overcome the foregoing and other disadvantages of known types of razors and to provide a razor which is characterized by its compactness when not in use and by its ease of transportation.

Another object of the invention is to provide a novel razor of attractive appearance.

Another object of the invention is to provide an inexpensive sturdy razor which can be stored in a small space.

A further object of the invention is to provide a razor unit that can be retracted into its position handle when not in use.

Yet another object of the invention is to provide a razor that is easily changed from an operative position to a collapsed, storage position.

The foregoing, and other objects of the invention, which will be made apparent as the specification proceeds, are achieved by the provision of a razor comprising a pair of blade holding means, a pair of spring arms adapted to mount the blade holding means but adapted to permit such means to be placed flush with at least one of the arms, a tubular container, and means slidably mounting one end of each of the arms in the container for retraction of the arms and blade holding means into the container and for extension of the arms from the container for operatively positioning the blade holding means.

Reference now is made to the accompanying drawings, wherein:

Fig. 1 is a side elevation of a razor embodying the principles of my invention with the razor in non-operative position and with part of the mounting handle removed;

Fig. 2 is an elevation of the razor of Fig. 1 in its extended position;

Fig. 3 is an elevation of the razor when in operative position;

Fig. 4 is a top plan of the razor blade securing unit; and

Fig. 5 is a vertical section on line 5—5 of Fig. 4. With regard to the details of the structure dis-

2

closed in the drawings, there is shown a tubular handle 1 which is provided with a tubular top 2 that is suitably removably engaged with the handle 1, as by a single thread 3. The handle 1 has an axially directed slot 4 formed therein which slot has a pin 5 with a head 6 thereon extending through it to engage with a block 7, which is snugly received in the handle for axial sliding movement therein. A prime feature of the invention is that a razor unit is associated with the block 7 and adapted to be extended from the handle 1 into its operative position or be retracted into the handle into non-operative position dependent upon the position of the block in the handle. The head 6 and pin 5 are used to slide the block and associated means in and out of the handle 1.

In order to position a razor unit on the handle 1, a U-shaped member of suitable composition, usually metal, and having two spring arms 8 and 9, is secured to the block 7, preferably by a screw 7a, extending into the inner end of the block 7, since the U-shaped member extends around the block with arms 8 and 9 lying against a pair of opposed flattened sides of the block.

The razor blade 10 of the razor of my invention, is positioned by suitable means which may comprise a small, flat, rectangular member 11 which has a hinge eye 12 formed thereon with a lip 13 extending therefrom, and a second small, flat rectangular member 14 which has a pair of hinge eyes 15 formed thereon. A hinge pintle 16 extends through the hinge eyes 12 and 15 with the eye 12 being snugly received between the eyes 15 to secure the members 11 and 14 together for relative pivotal movement therebetween. A V-shaped spring 17 is positioned between the lip 13 on the member 11 and the member 14 as shown in Fig. 4 to urge the members into blade engaging relation. The blade 10 may be positioned with its inner longitudinal edge against the forward edges of the hinge eyes 12 and 15.

To secure the razor blade unit to the arms 8 and 9, the member 14 also has an axially extending mounting bracket 18 usually formed integrally therewith and extending substantially perpendicularly therefrom. The bracket 18 has a pin 19 extending through it at each end and one of the pins 19 is adapted to be pivotally engaged with, or hinged on bifurcated ends 20 of the arm 8 while the other pin 19 is adapted to be temporarily engaged with bifurcated ends 21 of the arm 9. Thus the member 14 and the means carried thereby are adapted to be secured between the ends of the arms 8 and 9 in operative position, or to be disengaged from the arm 9 at which time the member 14 can be swung down to superimposed relation with the arm 8. In fact, the member 14 will usually swing to such superposed position normally by gravity action.

The arm 8 may be provided with a flat or straight section 8a in the bifurcated ends thereof to aid in moving the blade engaging unit from inoperative position to operative position as such section 8a will function as a stop for pivotal movement of the blade unit.

Fig. 1 shows that a cap 22, usually made of metal, may be secured in the end of the handle 1, which handle preferably is made of a section of tubular plastic material of suitable physical properties and attractive appearance.

The top 2 likewise may be secured to the handle 1 by any desired means and the top is formed of any desired material which might be a plastic or else could be a suitable metal, such as aluminum, or chrome-plated steel. The top 2 is shown with an integral end section and it is adapted to be placed on the handle 1 when the razor blade is withdrawn into the handle, or when the arm 9 is disengaged from the member 14. Of course, both the handle 1 and top 2 could be made with separate or integral closed end portions, as desired.

The top 2 preferably is made of such length as to receive therein a tube 23 which usually carries shaving cream so that the shaving unit of the invention would provide a compact, attractive article that can easily be carried on one's person but still be completely self-sufficient for shaving operations.

To facilitate carrying the shaving unit in non-operative position, a clip (not shown) of the kind carried by fountain pens could be positioned on the handle 1 or top 2, if desired.

In some instances, one might not require space for carrying shaving cream with the novel shave unit of the invention and in such event, no top, or an abbreviated end cover might be provided for the handle 1. Or, the cover could be so formed as to carry a reserve supply of razor blades in it.

It will be seen that the razor blade positioning members 11 and 14 can be formed of any suitable material, such as brass, and that the spring 17 is provided to urge the members into blade engaging relationship. The blade 10 can easily be removed by slight pressure on the lip 13 which will compress the spring and pivot the member 11 to the position indicated in dotted lines in Fig. 5. If desired, small protuberances could be formed on members 11 or 14 to mate with complementary recesses, or holes in the blade to lock it in position with relation to such members.

From the foregoing, it will be observed that a very attractive razor device is provided, which razor can easily be moved from operative to non-operative positions and that, when in inoperative position, is very compact. It also is so designed as to form an easily carried article, that is self-sufficient for shaving purposes.

It also should be noted that in some instances, it might be desired to make the razor of the invention without the retractability feature so that the blade holding members would be moved to a position superposed on the arm 8 and the top placed over the inoperative razor unit to facilitate its transportation.

While one presently preferred embodiment of the invention has been illustrated and described herein in detail, it will be realized that the scope of the invention is not limited thereto or thereby, but is defined by the appended claims.

What is claimed is:

1. A shaving article comprising a blade positioning device, spring arms engaged with the end

portions of said device, one end of one of said spring arms being removably engaged with said device and the same end of the other of said spring arms being pivotally engaged with said device so that said device can be disengaged from one of said spring arms and swung into a superimposed position with relation to the other of said spring arms, said spring arms being adapted to be superimposed when disengaged from said device, a tubular container having a longitudinally extending slot therein, a block slidably received in said container, means securing the remaining end of each of said spring arms permanently to said block, and means engaged with said block and extending through said slot in said container for moving said block axially of said container, said slot being of such length that said last named means can move said spring arms and device to an inoperative position completely within said container or to a position outside of said container whereat said device can be moved to operative association with said arms.

2. A shaving article comprising a blade positioning device, spring arms engaged with the portions of said device spaced from the ends thereof, one end of one of said spring arms being removably engaged with said device and the same end of the other of said spring arms being permanently pivotally engaged with said device so that said device can be disengaged from one of said spring arms and swung into a superimposed position with relation to the other of said spring arms, said last named spring arm having an end portion thereof extending therefrom substantially normally to the remainder of said arm, said arm end portion forming a stop to limit pivotal movement of said device away from such arm with which it can be superimposed, said spring arms being adapted to be superimposed when disengaged from said device and being connected by a base section spaced from the ends thereof engaged with said blade positioning device to form a U-shaped member, a tubular container having a longitudinally extending slot therein, a block slidably received in said container and having opposed flat side portions, said U-shaped member extending around said block with said arms lying against the flattened sides of same and being snugly received in said container, but with the said ends thereof adjacent said blade positioning device being adapted to extend from said container, means securing the base of said U-shaped member to said block, and means engaged with said block and extending through said slot in said container for moving said block axially of said container, said slot being of such length that said last named means can move said spring arms and device to an inoperative position completely within said container or to a position outside of said container whereat said device can be moved to operative association with said arms.

3. A shaving article comprising a blade positioning device, spring arms engaged with the end portions of said device, one end of one of said spring arms being removably engaged with said device and the same end of the other of said spring arms being pivotally engaged with said device so that said device can be disengaged from one of said spring arms and swung into a superimposed position with relation to the other of said spring arms, said spring arms being adapted to be superimposed when disengaged from said device, a tubular container having a longitudinally extending slot therein, a supporting mem-

ber slidably received in said container and snugly engaged with opposed portions of same, means securing parts of the said spring arms spaced from the blade positioning device at all times to said member, and means engaged with said member and extending through said slot in said container for moving said member axially of said container, said slot being of such length that said last named means can move said spring arms and device to an inoperative position completely within said container or to a position outside of said container whereat said device can be moved to operative association with said arms, said supporting member having opposed flattened side portions spaced from the said mem- 15

ber, said spring arms lying against the flattened side portions of said member.
